JOZEPH BLIK, OF THE HAGUE, NETHERLANDS, ASSIGNOR TO NAAMLOOZE VENNOOTS-
CHAP: TECHNISCH HANDELS-BUREAU "THABUR", OF THE HAGUE, NETHERLANDS.

ELECTRIC HEATING ELEMENT.

Application filed October 24, 1927, Serial No. 228,140, and in the Netherlands October 19, 1926.

The invention relates to electric heating elements for radiating heating fires in which the resistance wire is carried by a plurality of incombustible little blocks, which are arranged in a row in a guttershaped container of metal or other proper material.

With such heating elements it often happens that the blocks break and must be replaced. Therefore it is desirable to simplify 10 the replacement as much as possible so as to avoid lengthy repairs which require a special skilled staff.

Heating elements are known in which the vertical section of the container is shaped 15 such that the broken blocks may only be interchanged in that way that they are shoved out together with the adjacent blocks.

The great drawback of this construction is that if a block breaks it is not only necessary 20 to partially wind back the resistance wire but also to shove out of the container all the other blocks at one side of the broken block, it being mostly necessary to release the container at one end from the contact terminal 25 and to bend the metal container open at this end.

Further containers are known of which the blocks may be lifted out, but not without loosening at the same time one or more other 30 blocks.

According to the invention the construction makes use of a container having a vertical section which renders it possible to lift out one single block, and of separate fixing 35 means which makes each block independent from the others.

According to the invention the device is such that each block may be lifted out of the container in entire independency of the other 40 blocks, since the blocks are in the sides of the portions which are located inside the container, provided with one or more holes, into which are inserted screws or pins fastened to the container.

The drawing illustrates by way of example 45 some embodiments of the invention.

Fig. 1 is a side view of a heating element according to the invention.

Fig. 2 is a side and front view of an in- 50 combustible block according to the invention.

Fig. 3 is a side view of a block of a modified form of which

Fig. 4 is a top view.

The blocks are arranged in a container 1 which may for instance have a U-shaped vertical section, the blocks 2 being to that end provided with a foot 3. In said foot 3 there is at one side or at both sides a somewhat oblong hole 4 into which are inserted the ends of the screws or pins 5 which are screwed or placed in the side wall of the container 1. The hole 4 does not necessarily need to be oblong but the dimensions with respect to the screw or the pin 5 have been chosen such that the blocks are fastened so that they have sufficient play to allow them to freely expand when they become hot. The dimensions have been chosen so and the construction is carried out such, that the blocks have also a certain play in transverse direction, so that the risk that the blocks will break owing to heating or to other causes is nil.

For the rest the blocks have the usual form in which the resistance wire 8 is led between cams 9 of the blocks and further through 75 openings 10 to the adjacent block.

Thereby a radiation in all directions is obtained and the use of a reflector behind the element is then most effective.

In the embodiment according to Figs. 3 80 and 4 the resistance wire is not led through openings in the block but zigzag between the cams 9 of the blocks. With this arrangement there is then less risk that the wire will be damaged, whereas the heat will substantially 85 be radiated in a forward direction. The arrangement of the blocks in the container is further effected in the same manner as with the first mentioned embodiment.

The construction according to the invention 90 gives the advantage that the interchanging of broken blocks may be effected very quickly.

Assuming that in Fig. 1 the block A is burst then the resistance wire 1 is loosened at the 95 right hand end and drawn back (according to the construction illustrated in Figs. 3 and 4 it is sufficient to remove the wire from the block in question). Subsequently the screw 5 of the block A is unscrewed and the block 100

may easily be removed. The new block may immediately be placed whereafter the wire is again put in place.

What I claim is:

- 5 An electric heating element for radiating heat including a holder, a plurality of refractory blocks independently mounted in said holder and having slots therein, said blocks being arranged relative to each other to al-

low for expansion, a resistance wire carried 10 by said blocks and capable of detachment from each of them, and fastening means carried by said holder and engaging in said slots, said fastening means being removable to allow each block to be taken from the holder 15 without displacing any other block.

In testimony whereof I affix my signature.
JOZEPH BLIK.
